UNITED STATES PATENT OFFICE.

CHRISTIAN ANDRESEN, OF ST. LOUIS, MISSOURI, ASSIGNOR, BY DIRECT AND MESNE ASSIGNMENTS, TO INTERLOCKING HOOK AND EYE MANUFACTURING COMPANY, OF ST. LOUIS, MISSOURI, A CORPORATION OF MISSOURI.

HOOK AND EYE.

SPECIFICATION forming part of Letters Patent No. 755,603, dated March 29, 1904.

Application filed February 24, 1902. Renewed December 26, 1903. Serial No. 186,705. (No model.)

To all whom it may concern:

Be it known that I, CHRISTIAN ANDRESEN, of the city of St. Louis, State of Missouri, have invented certain new and useful Improvements 5 in Hooks and Eyes, of which the following is a full, clear, and exact description, reference being had to the accompanying drawings, forming a part hereof.

My invention relates to interlocking hooks 10 and eyes; and it consists of the novel features herein shown, described, and claimed.

My object is to construct an interlocking hook and eye in which there will be a yielding frictional resistance between the hook and eye during the operation of hooking and unhooking, so as to prevent the liability of 15 accidental unhooking.

A further object of my invention is to construct a hook and eye in such a manner that 20 when the hook and eye are properly stitched to the garment the operation of hooking and unhooking will not cut the threads.

My invention consists of the combination in 25 a hook and eye of a hook the bill of which is composed of two members, one of said members comprising two parallel bars and the other of said members comprising a third bar interposed between the two parallel bars, one of said members being bent outwardly, so as 30 to offset one member relative to the other and form a compressible enlargement on the bill, and an eye having restricted opening to receive said enlargement, the points of said eye which engage said enlargement being yielding or expansible, all arranged so as to create 35 a yielding frictional resistance between the hook and eye during the operation of hooking and unhooking and so as to make the eye follow the bill of the hook and pass over the 40 stitching, holding the hook in position.

Figure 1 is a plan of the eye attached to the garment, the garment being broken away to economize space. Fig. 2 is a plan of the hook attached to the garment, the garment being broken away to economize space. Fig. 3 is a 45 side elevation of the eye. Fig. 4 is a side elevation of the hook. Fig. 5 is a sectional view

of the eye. Fig. 6 is a sectional view of the hook. Fig. 7 is a view in elevation, showing the hook and eye interlocked and showing in 50 dotted lines the operation of unlocking.

Referring to the drawings in detail, the hook consists of the loops 8 and 9 to receive the stitching 10, the outer back bars 11 and 12, extending from the loops, semicircles 13 and 14, extending inwardly from the back bars, the front bars 15 and 16, extending backwardly from the semicircles 13 and 14, and the semicircle 17, connecting the ends of the front bars 15 and 16. 55

The front bars 15 and 16 form one member of the bill of the hook. The central back bar 18 extends from one of the loops 8 or 9 between the outer back bars 11 and 12. The semicircle 19 extends from the central back 60 bar between the semicircles 13 and 14, and the front bar 20 extends from the semicircle 19 between the front bars 15 and 16, said front bar 20 forming the other member of the bill 65 of the hook, and said member is bent to form the outwardly-projecting hump 21 as required to offset the outer member relative to the inner member and form an enlargement upon the bill of the hook. 70

The outer back bars 11 and 12 and the central back bar 18 form the shank. The semicircles 13 and 14 and the semicircle 19 form the bend. The front bars 15 and 16 and the front bar 20 form the bill. The shank, the bend, and the bill are composed of three substantially parallel bars, two of said bars being connected at the point of the bill and the free end of the third bar extending into the bill of the hook between the other two bars, said third bar having a hump extending outwardly 85 from the bill of the hook. 75

The hook as described is formed of a single piece of wire, and the bar 20 of the bill of the hook is at one end of the wire, so that said member swings freely between the bars 15 and 16 as required to make the enlargement of the bill of the hook yielding or compressible. 80

In forming the bill of the hook it is essential that it be composed of three bars, one of

which swings between the other two, so as to make three points of contact in passing through the eye, said points of contact being in the form of a triangle, so as to keep the hook from tipping one way or the other, as would be the case if only two bars were used. The opening through the eye-loop is broader than it is long, and if the hook was composed of two members which allowed the hook to tip it would get away from the frictional resistance produced by the restricting-bar in the eye.

The eye comprises the loops 22 and 23 to receive the stitching 24, the eye-loop 25 connecting the stitching-loops 22 and 23 and forming the opening to receive the bill of the hook, and the restricting-bar 26 connecting the opposite ends of the loops 22 and 23 and forming a yielding frictional resistance to be engaged by the enlargement on the bill of the hook in hooking and unhooking.

When the point of the bill of the hook is inserted into the loop 25, one member of the bill, comprising the bars 15 and 16, will engage the front portion of the loop, and the other member, comprising the bar carrying the hump 21, will engage the bar 26, and the enlargement on the bill of the hook will yield and the bar 26 will yield as required to create a yielding frictional resistance between the hook and eye, and the same resistance is created in removing the hook from the eye. This frictional resistance will cause the eye to slide along the bill of the hook over the stitching, thereby protecting the stitching from being cut by the eye. When the eye is in engagement with the hook, the bend of the hook will strike the restricting-bar 26 and hold the eye away from the stitches which secure the hook in place.

The essential feature of my invention is a hook having a bill composed of two members offset relative to each other, one of said mem-

bers being composed of two bars, between which the other member yieldingly operates as required to form a compressible enlargement upon the bill of the hook, and an eye having a restricted opening, said opening being expansible in the pressure of said enlargement.

I claim—

1. In a hook and eye, a hook comprising a shank, a bend and a bill, composed of three substantially parallel bars, two of said bars being connected at the point of the bill and the free end of the third bar extending into the bill between the other two bars, said third bar having a hump extending outwardly from the bill of the hook; and a suitable eye to receive the hook, said eye having a restricted opening, the inner wall of which coacts with said hump, substantially as specified. 50

2. In a hook and eye, a hook comprising a shank, a bend and a bill, composed of three substantially parallel bars, two of said bars being connected at the point of the bill and the free end of the third bar extending into the bill between the other two bars, said third bar having a hump extending from the bill of the hook outwardly; and a suitable eye to receive the hook; said eye consisting of a wire 65 bent to form a pair of stitching-loops, an eye-loop connecting the stitching-loops and forming an opening to receive the bill of the hook, and a restricting-bar connecting the opposite ends of the stitching-loops and extending into the eye-loop to engage the bill of the hook, 70 said restricting-bar being in the same plane as the eye-loop, substantially as specified. 75

In testimony whereof I affix my signature in presence of two witnesses.

CHRISTIAN ANDRESEN.
